UNITED STATES PATENT OFFICE.

JOSEPH F. BIGGS, OF RICHMOND, VIRGINIA.

COMBINATION RECORD RACK AND EJECTOR FOR CABINETS.

1,396,156.

Specification of Letters Patent.

Patented Nov. 8, 1921.

Application filed August 12, 1920, Serial No. 403,176. Renewed August 22, 1921. Serial No. 494,367.

To all whom it may concern:

Be it known that I, JOSEPH F. BIGGS, a citizen of the United States, residing at the city of Richmond, in the county of Henrico 5 and State of Virginia, have invented certain new and useful Improvements in Combination Record Racks and Ejectors for Cabinets, of which the following is a specification, reference being had to the accompanying drawings.

This invention relates to an improved combination record rack and ejector for talking machine cabinets and an object is to provide a rack of this kind which is movable forwardly and rearwardly and especially capable of ejecting a small record which, through error, has been placed in the wrong slot of the rack so as to permit the extraction of the small record.

Another object is to provide a record rack including a front piece suitably slotted preferably in staggered relation to hold the records likewise in such position to permit them to be easily grasped, in combination with a skeleton record rack back constituting a false back for the cabinet so that together with the lower ends of the slots of the front piece, the records may be supported.

Still another object is to provide a movable ejector or record rack back wherein means is provided for holding the back in different adjusted positions so that the rack may accommodate records of different diameters and to permit them to be easily extracted when needed for use.

A further object is to provide an adjustable back for the record rack wherein means is included for retracting the back to its normal position.

A still further object is to provide a record rack especially designed and adapted for use in connection with a talking machine cabinet wherein the cabinet is so constructed as to provide a space in the rear 45 of the cabinet for an amplifier. In other words, it is the aim to provide a record cabinet wherein suitable space is afforded for the record rack in the front portion thereof and an amplifier in the rear thereby still maintaining a compact form of cabinet and at the same time affording extraordinary accommodations for the amplifier and the rack.

Additionally the invention aims to provide a cabinet for the record rack or ejector, 55 wherein the interior of the cabinet is readily accessible for the purpose of making re-

pairs of any of the parts of the rack or the ejector or the parts of the amplifier and its allied elements.

While the United States Patent Number 60 1,325,617 issued to Joseph F. Biggs on December 23, 1919, sets forth and broadly claims the staggered relation of the record supporting slots of the front piece in combination with a record back which is stationary, the present invention aims to provide a record rack front piece having record receiving slots, regardless of their relative arrangement, in combination with a movable and adjustable record rack back capable of 65 movement toward and from the front piece enabling small records which have been misplaced in the wrong slots to be easily ejected in order to be grasped.

Therefore, it is also the aim to support the 75 records in staggered relation, with the back of the rack in its adjusted or uniform position, in order to permit the records to be easily grasped and extracted.

The invention also embodies a record rack 80 made up of an angle iron frame including back pieces connected to the frame so as to be engaged by the rear edges of the record so that together with the lower ends of the slots of the front piece, the records are supported 85 and in such a manner as to reduce the wear on the faces of the records owing to the edges of the records being engaged at the rear and near their lower edges toward the front.

A further object is the provision of a record rack particularly adapted in sectional cases, similar to sectional bookcases. In other words, it is the aim to employ sectional cases with sliding and swinging doors or 90 closures, either with paneled or glass fronts and in which cases or sections record racks are arranged. The purpose of this is that an owner of a talking machine when first purchased may have a small number of records 95 and in this case a single section or case may be used and as the number of records increases, additional cases or sections may be purchased thereby building up a large case 100 for a great number of records. Otherwise 105 the record rack is similar to that shown in the cabinet machine. Furthermore, it is obvious that the record racks may be used in stores for supporting the records and in this case an immense case may be constructed adjacent the side of the wall, either in a single 110 structure or in sections with the improved

record rack mounted therein either in a single large space or possibly one or two relatively large spaces or in a great number of compartments. In fact, a sectional case 5 as has heretofore been mentioned may be used in talking machine stores.

The invention comprises further features and combination of parts, as will be herein-after set forth, shown in the drawings and 10 claimed.

In the drawings:—

Figure 1 is a vertical sectional view through a talking machine cabinet transversely thereof showing the adjustable record rack back mounted therein and constructed in accordance with the invention, 15

Fig. 2 is a horizontal sectional view through the cabinet also disclosing the record rack back constructed in accordance 20 with the invention,

Fig. 3 is an enlarged detail perspective view of one end of the record rack back constructed in accordance with the invention, 25

Fig. 4 is an enlarged view of a single case showing a great number of slots in the front piece adapted for use in talking machine stores or in homes,

Fig. 5 is a fragmentary view of a sectional 30 case which may be used either in talking machine stores or in homes,

Fig. 6 is a sectional view on the line 6—6 through one of the sections of the sectional record case shown in Fig. 5, indicating the 35 single record rack back,

Fig. 7 is a detail sectional view through the ratchet stop, and

Fig. 8 is a detail perspective view of a modified form of stop wherein a set screw 40 is employed for holding the stop in different adjusted positions,

Fig. 9 is a perspective view of a sectional record cabinet;

Referring to the drawings, 1 designates 45 a talking machine cabinet which, though constructed in accordance with the talking machine cabinet set forth and claimed in the copending application Serial Number 403,175, filed August 12th, 1920, in the name 50 of Joseph F. Biggs, it may be otherwise constructed of any other suitable configuration. This cabinet is provided with sectional foldable doors or closures 2 hingedly united as shown and capable of being swung open and 55 folded upon themselves against the ends of the cabinet so as to permit of ready access to the records which are supported in the rack. In Fig. 9 the doors 2^a are hinged at their upper edges to the several cabinets, 60 which when put together as shown, constitute a sectional record cabinet.

Also the cabinet is of such design as to afford a compartment or space 3 at the rear of the record rack back for the reception of 65 an amplifier such as indicated at 4.

Arranged in the forward part of the cabinet is a cabinet front piece 5 which as in the patent heretofore mentioned constitutes one member of a record rack for the support of the records. In order to accomplish 70 this, this front piece is provided with a plurality of slots, which, though they may be arranged in various positions, are preferably staggered as in the aforementioned patent. 75

However, the staggered arrangement of the slots in the present case is greatly reduced, in other words, less exaggerated than in the said patent. Although it is the aim to use the staggered arrangement, it is obvious that it may be dispensed with if the occasion arises. 80

In order to utilize the slots, staggered or otherwise arranged as supports for records, a record rack back 6 is provided. 85 This record supporting rack, although it is skeleton in form constitutes a partition between the amplifier receiving space and the record rack compartment. The back comprises the end angle irons 7 and 8 which 90 are disposed vertically. The upper vertical angle irons 8 are disposed slightly in advance or offset forward of the lower angle irons 7 and it will be noted that these angle irons are relatively longer than one-half the 95 height of the cabinet so that the adjacent ends of the vertical angle irons overlap.

The overlapping ends of the angle irons are rigidly connected by the transverse plate 10 which is secured at 11 to the angle irons. 100 Also secured at 12 to the angle irons are the actuating bars 13. Pivotedly mounted on certain of the securing means 12 are links 14 which in turn are pivotally mounted as at 15 on the sides of the cabinet as in Figs. 1 and 105 3, thereby supporting the record rack back in the cabinet. The actuating bars 13 have their rear portions extending beyond the lower angle bar 7 and connected to the extended ends thereof are coil springs 15^a 110 which in turn are connected at 16 to the rear wall of the cabinet. By means of the coil springs 15^a, the angle irons 7 and 8 are held in contact with the stops 17 and 18.

These stops as in Figs. 1, 2 and 3 include 115 the ratchet bars 19 which are slidably mounted in the brackets or bearings 20 which are supported on the sides of the cabinet and secured thereto as at 21. The bearings or brackets have mounted therein 120 spring tensioned plungers 22 which bear down upon the ratchet bars to act to hold them in substantially horizontal positions. It is obvious that the bottoms of the openings of the brackets or bearings 20 have 125 teeth 20^a, which are engaged by the teeth of the ratchet bars 19, in order that the bars may be held in different positions.

It is obvious that these stops include the ratchet bars and may be set at any desired 130

- positions so as to limit the rearward movement of the record rack back. It is obvious that the spring tensioned plungers 22 may be dispensed with as well as the teeth on 5 the ratchet bars 19 and in lieu thereof plain bars 23 may be employed. These bars 23 may slidably engage in bearings such as indicated at 24 and may be held in different adjusted positions by the set screws 25. 10 The brackets 24 may be secured to the sides of the cabinet in the same manner as the brackets 20.

In Fig. 6 a single record rack back is employed and this style of back is especially 15 adapted for use in connection with single compartments or in compartments of single sections or cases as in Figs. 4 and 5, though it may be employed in connection with the usual talking machine cabinet. This single 20 record rack back is somewhat similar to the record rack back in Figs. 1, 2 and 3 to the extent that a single back piece 6^a connects opposite angle irons 7^a and there being the rigid actuating bars 13^a connected to the angle irons 7^a and braced relatively thereto by 25 the right angle piece 26. The single record rack back in Fig. 6 is also pivotally mounted upon a link 27 which in turn is pivotally mounted at 28 upon the sides of the case or 30 cabinet. Also in the construction of Fig. 6 suitable abutment stops 29 and 30 are employed. The stop 30 is similar to that shown in Fig. 8 and similar reference characters are therefore applied thereto. However, the 35 upper abutment stop 29 is slightly modified to the extent that it has a socket 31 receiving a substantially correspondingly shaped member 32 which is carried by each of the angle irons 7^a. The actuating bars 13 and 13^a 40 either in Figs. 1, 2 and 3 or in Fig. 6 are each provided with a depending handle 33 by which the bars may be manipulated.

The stops are arranged as desired so that the record rack backs may be engaged by the 45 rear edges of the records thereby permitting portions of the records to protrude beyond the front piece of the cabinet sufficiently to be grasped. Furthermore, it is to be noted that the slots in the front piece are preferably staggered so as to permit the records to 50 be easily grasped. The lower ends of the angle irons 7 and the upper ends of the angle irons 8 rest against the stops and are held in contact therewith by means of the coil 55 springs 15^a. When it is desired to remove a record, the actuating bars 13 may be moved or tilted upwardly or downwardly. If tilted upwardly, the angle irons 8 are fulcrumed upon the upper stops thereby permitting the 60 records below to be protruded sufficiently beyond the front piece in order that they may be grasped. If the actuating bars 13 are tilted downwardly, the upper angle irons 8 will tilt forwardly, to cause the upper 65 backs to move the records sufficiently beyond

the front piece as to permit them to be grasped. By means of a record rack back of this character, it is possible to eject a small record, which, through error, has been placed in the wrong slot of the rack so as to 70 permit the extraction of the small record.

When the actuating bars 13^a are tilted upwardly, the projections 32 will move in their sockets 31 of the upper stops 29 while the lower portions of the angle irons 7^a will tilt 75 forwardly. The lower record rack back 6^a will likewise move forwardly and cause the records to protrude beyond the front piece sufficiently to be grasped, particularly in view of the fact that the slots are staggered 80 so as to relatively offset the records.

In Figs. 4 and 5 it will be noted that the single record rack is adapted for use on the interior of the single structure of case or in the various compartments of the sectional 85 cases. In fact, the record rack back may be used in any form of compartment whether it is case or cabinet compartment or whether it is a covered compartment or a compartment formed by shelves, in fact it may be used in 90 any form of inclosure.

It will be noted that should a small record by mistake be placed in the wrong slot of the front piece, the drop handles may be grasped and the record rack back tilted as desired 95 against the tension of the springs 15^a and when so tilted, it is obvious that the edge of the small record will protrude through the slot of the front piece in a position where it may be easily grasped by the operator. 100

The front piece 5 is composed of a pair of laminations 34, with felt or other fabric 35 between them. The fabric is slotted correspondingly to the slots of the front piece so as to wipe the records when they are withdrawn. The design of construction herein shown is simply illustrative of the present embodiment of the invention, therefore, it is obvious that modifications of the details of construction, as may be governed by the 110 terms of the appended claims, may be adopted.

The invention having been set forth, what is claimed as new and useful is:—

1. The combination with a record cabinet, 115 of a front piece mounted therein and having record engaging means, a record rack back movably mounted in the cabinet and having relatively offset portions, one in advance of the other, both portions and said record engaging means adapted to be engaged by records for supporting them, tensioning means for the back, stops for the back, and means for actuating the back against the action of the tensioning means, for ejecting a record. 120

2. The combination with a record cabinet, 125 of a front piece mounted therein and provided with record supporting slots, a record rack back movable in the cabinet and being capable of advancement toward the front 130

piece for the ejection of a record, tensioning means for the rack back to move the same rearwardly, means connected to the rack back for manually moving the same toward 5 the front piece, and means for holding the rack back in different adjusted positions.

3. The combination with a record cabinet, of a front piece mounted therein and provided with record supporting slots, a movable record rack back in the cabinet to support the rear edges of the records and being capable of advancement toward the front piece for the ejection of a record, tensioning means for the rack back to move the same 10 rearwardly, means connected to the rack back for tilting the rack back for moving either of the upper and lower parts toward the front piece, ratchet holding means for limiting the upper and lower parts of the 15 rack back in different adjusted positions 20 against the action of the tension means.

4. The combination with a record cabinet, of a front piece mounted therein and provided with record supporting slots, ratchet stops mounted on the inner faces of the sides 25 of the cabinet at the top and bottom, a record rack back engaging said stops, spring means connecting the record rack back and the back of the cabinet to hold the upper 30 and lower ends of the record rack back in contact with the stops, and means carried by the record rack back and being manually operable for tilting the record rack back whereby its upper or lower end may be 35 moved forwardly.

5. The combination with a record cabinet, of a front piece mounted therein and provided with record supporting slots, a record rack back mounted to be tilted on an axis 40 transversely of the cabinet and adapted to be engaged by the rear edges of the records, the forward lower portions of the edges of which engage the lower ends of the supporting slots, and adjustable stops for the upper 45 and lower ends of the record rack back.

6. The combination with a record cabinet, of a front piece mounted therein and provided with record supporting slots, a record rack back mounted to be swingingly and 50 bodily advanced on an axis movable transversely of the cabinet and adapted to be engaged by the rear edges of and to support the records, the forward lower portions of the edges of which engage the lower ends of 55 the supporting slots, adjustable stops for the upper and lower ends of the record rack back, and tensioning means for holding the record rack back in engagement with the stops.

60 7. In a record cabinet, means in the front part of the cabinet to be engaged by the forward edges of the records, a device mounted to move on an axis movable transversely of the cabinet and having means to be engaged

by the rear edges of the records to support 65 the records, swinging means for suspending said device, and means manually actuated and carried by the device for moving the same on said axis.

8. In a record cabinet, means in the front 70 part of the cabinet to be engaged by the forward edges of the records, a device mounted to move on an axis transversely of the cabinet and having means to be engaged by the rear edges of the records, means for suspending 75 said device, adjustable stops for the upper and lower ends of said device, tensioning means for the device to hold it in contact with the stops, and means manually actuated and carried by the device for moving 80 the same on said axis.

9. In a record cabinet, means in the forward part of the cabinet to support the forward edges of the records, a tiltable member 85 in the cabinet spaced to the rear of said means a distance less than the diameter of the record for engagement with the rear edges of the records to support the same, means for swingingly and tiltably supporting 90 said member, and means manually actuated for tilting the member to move the records forwardly.

10. In a record cabinet, means in the forward part of the cabinet to support the forward edges of the records, a tiltable member 95 in the cabinet spaced to the rear of said means a distance less than the diameter of the record for engagement with the rear edges of the records to support the same, means for tiltably supporting said member, 100 stops for the upper and lower portions of said member, one of said stops acting as a fulcrum for said member, and means manually actuated for tilting the member to move the records forwardly.

105 11. In a record cabinet, means in the forward part of the cabinet to be engaged by the edges of the records for supporting the same, a rack back adapted to be engaged by the rear edges of the records to assist in supporting 110 them, said rack back being bodily movable on an axis movable transversely of the cabinet to eject a record.

12. In a record cabinet, a support in the front of the cabinet to be engaged by the 115 edges of the records, adjustable stops, a record rack back in contact with the stops and adapted to engage the rear edges of the records to assist in supporting them, said rack back being movable on an axis transversely of the cabinet for ejecting a record.

120 13. In a record cabinet, the coöperative supports adapted to engage the forward and rear edges of the records to support the same, one of said supports constituting a 125 record rack back and an ejector movable bodily to eject a record, loosely suspended means for said ejector support, adjustable

- stops for the record rack back, and tensioning means to hold the back in contact with the stops.
14. In a record cabinet, means in the forward part of the cabinet to be engaged by the forward edges of upper and lower tiers of records, a rack back advanceable toward said means to partially eject either tier of records or both simultaneously.
- 10 15. In a record cabinet, means in the forward part thereof to be engaged by the lower forward edges of upper and lower tiers of records, and a rack back advanceable on an axis advanceable transversely of the cabinet, to eject either tier of records or both simultaneously.

In testimony whereof I hereunto affix my signature.

JOSEPH F. BIGGS.
